RAILWAY SIGNALING

Ronald A. McCann, Swissvale, Pa., assignor to
 The Union Switch & Signal Company, Swiss-
 vale, Pa., a corporation of Pennsylvania

Application February 15, 1936, Serial No. 64,094

13 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of three sections in the rear of an occupied section. Each distinctive control is effective to cause a corresponding aspect 10 of the associated wayside signal, whereby there is produced a three-block, four-indication, system of signaling.

I will describe one form of apparatus embodying my invention, and will then point out the 15 novel features thereof in claims.

The accompanying drawing is a diagrammatic view illustrating one form of apparatus embodying my invention.

Referring to the drawing, the reference characters 8 and 9 designate the rails of a stretch of 20 railway track along which traffic normally moves in the direction indicated by the arrow. These rails are divided by insulated joints 14 into a plurality of track sections W—X, X—Y, and Y—Z.

25 Each track section is divided by insulated joints 14 into at least two subsections 1T, 2T, 3T, 4T, etc. Each subsection is provided with a track circuit which includes a track battery 15 connected across the rails at one end of the subsection and a track relay, designated by the reference character R with a prefix the same as the reference character of the associated subsection, connected across the rails at the other end of the subsection.

35 To govern the passage of trains through the stretch of railway, a wayside signal designated by the reference character S with a suitable distinguishing prefix is provided for each track section. Each of these signals comprises a top unit 40 T and a lower unit L. These units may take any one of several forms of signal mechanism such as semaphore, color light, searchlight, or position light. As here shown, each top unit is a semaphore arm capable of assuming a horizontal or "stop" position, a 45° or "caution" position, and a vertical or "proceed" position; and each bottom unit is a semaphore arm capable of assuming a horizontal or "stop" position and a vertical 45 or "proceed" position.

50 Each section is provided with a polarized signal control line relay designated by the reference character HD with a prefix the same as the prefix in the reference character of the associated signal.

Each section is also provided with a neutral signal control line relay designated by the reference character H with a prefix the same as the prefix in the reference character of the associated signal.

5 Each polarized signal control relay HD is directly connected to a polarized line circuit which is controlled by the track relays of the section with which the polarized relay is associated as well as by the H relay and HD relay of the section in advance.

10 Each neutral signal control relay H is also provided with a polarized line circuit, one wire of which is common to the line circuit for the associated polarized relay. Each relay H is connected to its polarized line circuit through an asymmetric unit, here shown as a full wave rectifier, and designated by the reference character Q with a prefix the same as the prefix of the associated neutral relay. It will be readily apparent that although the relays H are connected 15 to polarized circuits, these relays, due to the valve action of the rectifiers, will be energized in the same direction regardless of the polarity of the line current.

20 25 It will be noted that each rectifier Q is connected to its line circuit through a resistor designated by the reference character P with a prefix the same as the prefix of the associated rectifier. The resistors P are connected in the line circuits to prevent excessive current flow in the event of the associated rectifier becoming short-circuited.

20 30 It will also be noted that since one line wire is common to both polarized line circuits, only three line wires are required between signals.

35 The manner in which the signals are controlled to cause the display of the different aspects will best be understood by tracing the circuits and explaining the operation of the apparatus simultaneously.

40 45 A train is indicated diagrammatically at K in the subsection 7T immediately to the right of location Z. The train shunt of train K will de-energize the track relay 7TR in the usual manner. Both line relays 13H and 13HD will be without energy due to front contacts 16, 17, and 18 of relay 7TR being opened. The signal 13S, therefore, is displaying both its semaphore arms in the horizontal position to indicate "stop".

45 50 The relay 12H for signal 12S is energized over a line circuit which passes from terminal B of a suitable source of current, at signal 13, through back point of contact 21 of relay 13HD, front contact 22 of relay 6TR, wire 22A, front contact 23 of track relay 5TR, resistor 12P, rectifier 12Q, 55

relay 12H, front contact 24 of relay 5TR, wire 24A, front contact 25 of relay 6TR, and back point of contact 26 of relay 13HD to terminal C of the same source of current.

5 Since relay 12H is energized and relay 12HD is deenergized, top semaphore T of signal 12S is energized over a caution circuit which passes from terminal B through front contact 28 of relay 12H and semaphore T to terminal C. The 10 signal 12S, therefore, is displaying its top semaphore arm in the 45° position and its lower semaphore arm in the horizontal position to indicate "approach next signal prepared to stop".

The relay 11H for signal 11S is energized over 15 a line circuit which passes from terminal B, at signal 12, through back point of contact 30 of relay 12HD, front contact 31 of relay 4TR, wire 32, front contact 33 of track relay 3TR, resistor 11P, rectifier 11Q, relay 11H, front contact 34 20 of relay 3TR, wire 35, front contact 36 of relay 4TR, and back point of contact 37 of relay 12HD to terminal C. Relay 11HD is energized in the reverse direction over a line circuit which passes from terminal B, at signal 12, through back 25 point of contact 38 of relay 12HD, front contact 31 of relay 4TR, wire 32, front contact 33 of relay 3TR, relay 11HD, front contact 38 of relay 3TR, wire 39, front contact 40 of relay 4TR, front contact 41 of relay 12H, and back point of contact 37 of relay 12HD to terminal C.

Since relay 11H is energized and relay 11HD is energized in the reverse direction, the caution circuit for the top semaphore T of signal 11S will remain closed over a path which passes from 35 terminal B through front contact 42 of relay 11H and semaphore T of signal 11S to terminal C; and a proceed circuit for the lower semaphore L of signal 11S is energized over a path which passes from terminal B through front contact 43 40 of relay 11HD, reverse polar contact 44-45 of relay HD, and lower semaphore L of signal 11S to terminal C. Signal 11S, therefore, is displaying its top semaphore arm T in the 45° position and its lower semaphore arm L in the vertical position to indicate "approach next signal at 45 medium speed".

The relay 10H for signal 10S is energized over 50 a line circuit which passes from terminal B, at signal 11, through front point of contact 46 of relay 11HD, front contact 47 of relay 2TR, wire 48, front contact 49 of relay 1TR, rectifier 10Q, relay 10H, resistor 10P, front contact 50 of relay 1TR, wire 51, front contact 52 of relay 2TR and front point of contact 53 of relay 11HD to terminal C. Relay 10HD is energized in the normal direction over a line circuit which passes from terminal B, at signal 11, through front point of 55 contact 46 of relay 11HD, front contact 54 of relay 11H, front contact 55 of relay 2TR, wire 56, front contact 57 of relay 1TR, relay 10HD, and thence to terminal C through front contact 50 of relay 1TR over the same path as just described for relay 10H.

Since relay 10H is energized and relay 10HD is 60 energized in the normal direction, the caution circuit for the top semaphore T of signal 10S will remain closed over a path which passes from terminal B through front contact 58 of relay 10H and semaphore T to terminal C, and a proceed circuit for the top semaphore T is closed over a path which passes from terminal B through front contact 59 of relay 10HD, normal polar contact 44-60 of relay 10HD and semaphore T to terminal C.

75 Signal 10S, therefore, is displaying its top

semaphore arm T in the vertical position and its lower semaphore arm L in the horizontal position to indicate "proceed at normal speed".

Since both relays 10H and 10HD are energized, it will be apparent that both line circuits for the section next in rear of location W, are energized by current of proper polarity so that the signal (not shown) controlled by such rear line circuit is displaying the normal proceed indication.

When the train K vacates the section immediately to the right of location Z, relay 12HD will become energized in the reverse direction so that relay 11HD will become energized in the normal direction to cause signal 11 to display the 15 normal proceed indication.

From the foregoing description it is apparent that I have provided a simple and reliable means for controlling a three-block, four-indication, signaling system which requires but three line control wires between signals, and which requires direct current energy only.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track having a track circuit including a track relay, a signal for said section capable of assuming several distinctive aspects, a polarized line relay and a neutral line relay for jointly controlling the different aspects of said signal, a first polarized line circuit including a contact of said track relay for governing said polarized relay in accordance with traffic conditions in advance of said section, a second polarized line circuit including a contact of said track relay as well as a portion of said first line circuit for governing said neutral relay, and a rectifier for connecting said neutral relay to said second polarized line circuit thereby preventing the release of said 45 neutral relay during pole changing periods.

2. In combination, a stretch of railway track, a signal for said stretch capable of assuming several distinctive aspects, a polarized line relay and a neutral line relay for jointly controlling the different aspects of said signal, a polarized line circuit for governing said polarized relay in accordance with traffic conditions in advance of said signal, another polarized line circuit including a portion of the first polarized line circuit for governing said neutral relay in accordance with traffic conditions in advance of said signal, and an asymmetric unit for connecting said neutral relay to said other polarized line circuit.

3. A railway signal system comprising, a stretch of railway track divided into a plurality of track sections each having a track circuit including a track relay, a first line circuit for each section controlled by the associated track relay, a second line circuit for each section also controlled by the associated track relay, a polarized relay for said first line circuit, a neutral relay for said second line circuit, means controlled by each polarized relay for supplying current to the second line circuit for the section next in rear for controlling the neutral relay of that line circuit, means controlled jointly by the polarized relay and the neutral relay of each section for reversibly controlling the first line circuit for the section next in rear for controlling the polarized 75

relay of that line circuit, and traffic governing means for governing the passage of trains along said stretch controlled by said polarized and neutral relays.

5 4. A railway signal system comprising a stretch of railway track divided into sections each having a track circuit including a track relay, two relays for each section, a first line circuit for controlling one of said relays and including a contact of the track relay for the section with which said one relay is associated, a second line circuit for controlling the other of said relays and also including a contact of said track relay, means controlled by said two relays 10 for reversibly supplying current to the first line circuit for the section next in rear of the associated section, means controlled by one of said relays for supplying current to the second line circuit for the section next in rear of the associated section, and signaling means for each section controlled jointly by said two relays of the section.

5 5. A railway signal system comprising, a stretch of railway track divided into sections, 25 two polarized line circuits for each section controlled by traffic conditions in advance of the associated section, a polarized relay for each section and connected to one line circuit of the associated section, a neutral relay for each section 30 and connected through a rectifier to the other of the line circuits of the associated section, and signaling means for each section controlled jointly by said two relays of the section.

6. A railway signal system comprising; a first, 35 a second and a third consecutive track section over which traffic normally progresses in the order named; a polarized line relay and a neutral line relay for each section, means controlled by a train occupying the third section effective to deenergize both the polarized and neutral relays of that section, means effective to deenergize the polarized relay for the second section when the neutral relay for the first section is deenergized, means for energizing the neutral relays for both 40 the second and first sections as long as said second and first sections are unoccupied, means for energizing in the reverse direction the polarized relay for the first section, said means being effective when the polarized relay for the second section is deenergized and the neutral relay for the second section is energized, a signal for the third section caused to indicate stop when both its polarized and neutral relays are deenergized, a signal 45 for the second section caused to indicate a restrictive indication when its polarized relay is deenergized and its neutral relay is energized, and a signal for the first section caused to indicate a less restrictive indication when its polarized relay is energized in the reverse direction 50 and its neutral relay is energized.

7. A railway signal system comprising; a first, a second, a third and a fourth track section over which traffic normally progresses in the order named; a polarized line relay and a neutral line 55 relay for each section, means controlled by a train occupying the fourth section effective to deenergize both the polarized and neutral relays of that section, means for deenergizing the polarized relay for the third section when the neutral 60 relay for the fourth section is deenergized, means for energizing the neutral relays for the first and second as well as the third section as long as said sections are unoccupied, means for energizing the polarized relay for the second section in the reverse direction when the neutral relay for the 65

third section is energized and the polarized relay for the third section is deenergized, means for energizing the polarized relay for the first section in the normal direction when the neutral relay and the polarized relay for the second section are both energized, and signaling means controlled by the last mentioned relays.

8. A railway signal system comprising, a stretch of railway track divided into sections each having a track circuit including a track relay, two line 10 relays for each section one polarized and one neutral, a line circuit for governing each polarized relay and another line circuit for governing each neutral relay, both said line circuits including a contact of the track relay for the section with which said line relays are associated, means controlled by said two line relays for selectively supplying current of normal or reverse polarity or supplying no current to the line circuit for governing the polarized relay for the section next in rear, 15 means controlled by said polarized relay for supplying current to the line circuit for governing the neutral relay for the section next in rear, and a signal controlled by said two line relays of a section and arranged to have a first aspect when both relays are deenergized, a second aspect when the polarized relay is deenergized and the neutral relay is energized, a third aspect when the polarized relay is energized in the reverse direction and the neutral relay is energized, and a fourth aspect 20 when the polarized relay is energized in the normal direction and the neutral relay is energized.

9. A railway signal system comprising; a first, a second and a third track section over which traffic normally progresses in the order named, 25 two line relays for each section one polarized and one neutral, means including a track relay for deenergizing both line relays for the third section when that section is occupied by a train, means for deenergizing the polarized relay of the 30 second section and for energizing the neutral relay of the second section when both line relays of the third section are deenergized, means for energizing the polarized relay for the first section in the reverse direction when the polarized relay 35 for the second section is deenergized and the neutral relay for the second section is energized, a signal for said first section, and means including a reverse polar contact of the polarized relay for the first section for causing said signal to 40 display an aspect indicating that the third section is occupied.

10. A railway signal system comprising, a stretch of railway track divided into track sections each such section having a track circuit 45 including a track relay, a first polarized line circuit for each section and comprising two line wires, a second polarized line circuit for each section including another line wire and one of the line wires of the associated first polarized line 50 circuit, a polarized line relay connected to each said first line circuit, a neutral line relay connected to each said second line circuit through a rectifier, and means including the associated track relay for governing both said first and said second line circuits for each section whereby a distinctive control is effected for each of three consecutive track sections to the rear of an occupied section.

11. In combination, a section of railway track, 70 a signal for said section, a polarized line relay for controlling said signal, a polarized line circuit for governing said polarized relay, a neutral relay also for controlling said signal and governed by another polarized line circuit, traffic con- 75

trolled means for governing said two line circuits, and means for maintaining the energization of said neutral relay in one direction regardless of the polarity of said other line circuit thereby preventing the release of said neutral relay during pole changing periods.

12. In combination, a section of railway track, a signal for said section, a polarized line relay for controlling said signal, a first polarized line circuit for governing said polarized relay, a second polarized line circuit which changes its polarity when the polarity of said first line circuit is changed, a neutral relay also for governing said signal and governed by said second polarized line circuit, and a rectifier for connecting said neutral relay to said second polarized line circuit thereby preventing the release of said neutral relay during pole changing periods.

13. In combination, a section of railway track,

two relays one polarized and one neutral, a polarized line circuit and a neutral line circuit for governing said polarized and neutral line relays respectively, track circuit means for governing both said line circuits, means for energizing said neutral line circuit, means including a pole changer governed in accordance with traffic conditions in advance of said section for governing said polarized line circuit, a signal for said section including a first indication unit and a second indication unit, a circuit for said first unit including only a front contact of said neutral relay, another circuit for said first unit including only a front neutral contact and a normal polar contact both of said polarized relay, and a circuit for said second unit including a front neutral and a reverse polar contact both of said polarized relay.

RONALD A. McCANN.
